SHIP LOG

Filed May 14, 1928

UNITED STATES PATENT OFFICE

JEFFERY WALKER, OF BIRMINGHAM, ENGLAND

SHIP LOG

Application filed May 14, 1928, Serial No. 277,722, and in Great Britain July 7, 1927.

This invention relates to ship logs of the submerged type, that is to say, wherein the rotator projects into the water from the hull of the ship whereon it is carried by a tubular housing, and the invention has primarily for its object to secure greater efficiency in a log having a rotator of the screw type, while it also has for its other objects to prevent fouling of the rotator by sea-weed, or other like 10 obstructions, to avoid sand, grit or water being driven into the bearings of the rotator spindle, and to enable the log mechanism and bearings to be lubricated automatically.

Accordingly, a ship log of the type specified 15 is operated by means of a rotator which with its housing is disposed at an inclination to the hull of the ship and directed towards the stern thereof. Further, the rotator is provided with vanes whereof the acting faces 20 present helical surfaces which are so contoured that as the rotator moves each vane presents to the water the maximum effective surface at right angles or substantially at right angles to the direction of the flow of 25 water past the rotator.

The aforesaid housing extends below the lower bearing of the rotator spindle thereby affording protection against the entry of grit thereinto as the ship moves through the water, 30 the lower edge of the housing being either inclined relatively to or parallel with the hull of the ship.

If desired, the housing may be prolonged 35 at its lower extremity to protect the rotator in action and it may also, if desired, be designed so as to offer axial support to the foot of the rotator spindle.

In order to assist lubrication of the mechanism contained by the housing, the rotator 40 spindle may be helically grooved or otherwise adapted to convey lubricant, and an oil container having a ball or other suitable automatic valve may be located above and in communication with the housing, the lubrication being further assisted by the formation of

a partial vacuum around the lower bearing of the rotator spindle, due to the shrouding of the bearing by the housing, and continuing so long as the suction created at the lower bearing is sufficient to overcome the static 50 pressure of the water.

Or, means may be provided for balancing the pressure of the lubricant in the container to compensate for the static pressure of the water and to ensure automatic lubrication at 55 low speeds.

One constructional embodiment is illustrated by way of example in the accompanying drawings, in which, Figure 1 is a sectional elevation and Figure 2 is a detail view of a 60 modified shape of housing for the rotator spindle and its associated mechanism.

A represents the hull of the vessel above an aperture in which is fixed an inclined tubular bracket B provided with a valve C adapted 65 to be operated by a handwheel D when the log is not in situ.

Into the inclined bracket B is fitted removably a tubular housing E which projects through the hull towards the stern of the 70 vessel and into which is led an electric cable F connecting the chart room receiver with make-and-break mechanism (not shown) which in turn is connected operatively by a flexible shaft F¹ with the transmission mech- 75 anism G whereof the primary spindle H is coupled at J to a spindle K carrying at its lower extremity the rotator L.

The rotator spindle K is supported at its upper end laterally by a ball bearing K¹ and 80 axially by a ball bearing K² both accommodated in a sleeve K³ fitted appropriately into the housing E; a ball bearing K⁴ accommodated in a sleeve K⁵ supports the rotator spindle K laterally near its point of exit from the 85 lower end of the housing E and is enclosed by a ring K⁶ screwed into the lower end of the housing E and fitting closely around an enlargement or collar K⁷ formed on the rotator spindle K just below the bearing K⁴. 90

The sleeves K^3 and K^5 are connected rigidly by a tubular distance piece K^8 screwed into the sleeves K^3 and K^5 .

Upon the lower end of the spindle K is mounted the rotator L which is composed of a plurality of vanes whereof the acting faces present helical surfaces which are so contoured that as the rotator moves each vane presents to the water the maximum effective surface approximately at right angles to the direction of the flow of water past the rotator, thus rendering the rotator efficient at low speeds.

At its bottom end the surface of the housing E is tapered and the extreme lower edge is arranged to overlap slightly the upper end of the rotator L . Instead of being inclined to the hull A as shown in Figure 1 the lower edge of the housing E may be parallel with the hull as shown in Figure 2; the arrangement in both cases being such as to shroud the bearing K^4 .

This shrouding of the bearing K^4 , besides affording a protection against the entry of grit also, in conjunction with the inclination of the housing, induces, at high speeds, a partial vacuum around the bearing K^4 as the ship moves through the water, advantage being taken of this effect to provide automatic lubrication of the mechanism and the bearings contained by the housing E .

There is accordingly mounted at the head of housing E a lubricant container M in communication with the interior of the casing of the flexible shaft F^1 by way of ball-valves M^1 and M^2 , and flows through said casing to the transmission G and thence past the lower bearing of the latter to the upper bearings K^1 and K^2 of the rotator spindle K . The rotator spindle K is helically grooved as at K^9 in order to convey along it the lubricant which is induced to flow out of container M by the suction due to the partial vacuum set up around bearing K^4 when the log is in operation.

It will be appreciated that, instead of projecting downwardly through the bottom of the vessel, as illustrated, the housing may be directed laterally through the hull, as will be easily understood by regarding Figure 1 as a sectional plan-view. Further, the invention is not limited to a rotator of the helical type, but is equally applicable to a rotator having straight vanes, which, however, would be less efficient than the former at slow speeds.

By means of the above described construction and arrangement, increased efficiency is obtained in a log having a rotator of the screw type, and a submerged log is completely protected against the injurious effects, upon the bearings of the rotator spindle, of sand, grit or water, while at the same time the inclination of the tubular housing and the form of the screw rotator cause sea weed, jelly fish and the like to pass over the log with-

out obstructing it. Further, the lubrication of the mechanism is assured, which is an important factor in securing and maintaining the necessary accuracy and efficiency in a log.

What I claim is:—

1. A ship log comprising a tubular bracket having means for supporting it at an inclination over an opening in the hull of a ship with its lower end directed toward the stern of such ship, a tubular housing removably fitting within said tubular bracket to project into the water, a rotator spindle extending axially of said housing, a bearing within said housing to support said spindle adjacent its upper end, a second bearing in said housing adjacent the lower end of the latter to support said rotator spindle adjacent its lower end, and a rotator carried by the lower end of said rotator spindle, said rotator having its upper end extending into the lower end of said housing, said rotator having its lower end projecting beyond the housing and comprising vanes each of such a contour as to present the maximum effective surface at substantially a right angle to the flow of water past said rotator.

2. A ship log according to claim 1 including a lubricant container and means connecting the lubricant container with the tubular housing so that lubricant is drawn through the tubular housing by the rotation of the rotator.

3. A ship log comprising a tubular bracket having means for supporting it at an inclination over an opening in the hull of a ship with its lower end directed toward the stern of such ship, a tubular housing removably fitting within said tubular bracket with its lower end immersed in the water, a rotator spindle extending axially of said housing, a bearing in said housing adjacent the lower end of the latter to support said spindle adjacent its lower end, and a rotator carried by the lower end of the rotator spindle, said rotator having its upper end extending into the lower end of said housing, said rotator having its lower end projecting beyond the housing and comprising vanes of which the acting faces each presents a helical surface disposed substantially at a right angle to the direction of flow of water past the same.

4. A ship log comprising a tubular bracket having means for supporting it in an inclined position adjacent the stern of a ship with its lower end directed rearwardly of the stern of such ship, a tubular housing removably fitting within said bracket with its lower end immersed in the water, a lubricant container, means connecting said lubricant container with said tubular housing, a spindle extending longitudinally of said housing and rotatable therein, a bearing for said spindle in said housing adjacent the lower end of the latter, and a rotator carried by the lower end of said spindle beyond the lower end of said

housing and comprising a plurality of vanes of which the acting faces present helical surfaces directed at substantially right angles to the flow of water past the same, said housing having at its lower end an extension surrounding the upper ends of said vanes, whereby the rotation of said rotator causes a partial vacuum within said housing and a flow of lubricant from said container through said housing to said bearing.

10 In testimony whereof he affixes his signature.
